UNITED STATES PATENT OFFICE.

ANDRÉ BLONDEL, OF PARIS, FRANCE, ASSIGNOR TO GENERAL ELECTRIC COMPANY, A CORPORATION OF NEW YORK.

ARC-LAMP.

1,220,063.

Specification of Letters Patent. Patented Mar. 20, 1917.

Application filed March 20, 1914. Serial No. 826,014.

To all whom it may concern:

Be it known that I, ANDRÉ BLONDEL, a citizen of the French Republic, residing at Paris, France, have invented certain new and useful Improvements in Arc-Lamps, of which the following is a specification.

My invention has reference to an arc lamp, and more particularly to a lamp of the inclosed flame type. In lamps of this character fumes are evolved from the arc which carry solidifiable products of combustion. These products of combustion should not be allowed to deposit upon the inclosing globe to any appreciable extent, particularly that region of the globe through which the most useful light passes, as such deposit obscures the light and seriously impairs the efficiency of the lamp. One object of my invention is the provision of a simple and efficient circulatory system for the gases comprising a depositing chamber or chambers located above and remote from the arc, the walls of which are preferably exposed to the atmosphere so that they are kept cool, and means comprised within said system for inducing a circulation through said depositing chamber where the solidifiable matter carried by the gases is largely deposited so that the gases which are returned to the inclosing globe from the chamber are sufficiently relieved of the solidifiable products of combustion to prevent appreciable deposit on the inclosing globe.

Another object of my invention is the provision of a novel organization of parts for inducing a circulation of gases within the circulatory system comprising a chamber located immediately above the arc in which the gases evolved from the arc are primarily received and from which they are conducted to an upper, more remote chamber through suitable passages, other passages conducting the gases from said upper chamber past and below the lower chamber where they are returned to the inclosing globe.

Other novel features of my invention will appear in the description and will be particularly pointed out in the claim.

For a fuller understanding of my invention, reference may be had to the accompanying drawings, which show one embodiment of the same, and in which Figure 1 is a vertical section of a lamp taken on the

line 1, 1, Fig. 3, showing the casing in elevation; Fig. 2 is a similar section taken on the line 2, 2, Fig. 3; Fig. 3 is a transverse section taken on the line 3, 3, Fig. 1; Fig. 4 is a perspective view of the bottom plate of the lamp with the tubes secured thereto; and Fig. 5 is a perspective view of the reflector showing the top of the inner inclosing globe seated against the same.

In the drawings, 1 is a shell, preferably cylindrical in form, located at the top of the lamp and closed at the top by a plate 2, and at the bottom by a plate 3. The shell is provided with a septum or partition 4 which divides the space within the shell into two chambers A and B which constitute depositing chambers for the solidifiable products of combustion evolved from the arc. It will be seen that the walls of the shell 1 are exposed to the atmosphere and this tends to keep the walls cool and to promote the deposit of products of combustion thereon. The shell 1 is provided with any convenient number of lateral openings which are closed by plugs through which the chambers may be cleaned in any desired manner. A tube 6 passes axially through the shell 1 and is secured to the upper and lower plates 2 and 3 and preferably made integral therewith. The lamp is suspended by an eye-bolt 7 passing through the tube 6 and provided at its lower end with a nut 8 which is received in a counter-bored opening 9. Tubes 10, 10^a, suitably spaced from one another, are secured to the lower plate 3 of the shell 1 in any convenient manner and communicate with the depositing chamber A. Two other tubes 11, 11^a are similarly secured to the shell and communicate with the depositing chamber B. A bottom plate 12 for the lamp is provided with hollow bosses 13, 13^a on its upper side, in which the lower ends of the tubes 10, 11, and 10^a, 11^a, respectively, are received and to which they are secured in any suitable manner, the tubes communicating with the hollows formed within said bosses. The bottom plate 12 is provided with an annular flange 12^a depending from near its outer edge, as shown in Figs. 1, 2 and 4. An annular plate 14 is provided with a vertical flange 15 which is received about the annular flange 12^a of the bottom plate, suitable packing being placed between the flange 15 and the part 110

12^b of the bottom plate which projects horizontally beyond the flange 12^a. The plate 14 is also provided with an upwardly and outwardly inclined flange 16, against which 5 the outer globe 19 is seated and against which it is held by an annular ring 20. The inner inclosing globe 21 is seated in the usual cup or plate 22 which is in turn supported on a spring 23. The spring is carried 10 on the usual cross-arm 24, the ends of which are secured to the lower ends of rods 25, the upper ends of the latter being secured in the plate 14.

An economizer 27, through which the 15 upper electrode 28 passes in the usual manner, is secured to the bottom plate 12. A reflector 29 surrounds the economizer 27 and is provided with an opening 30 considerably larger than the economizer and through 20 which the fumes ascending from the arc may pass. The reflector 29 is provided with an annular flange 31, which extends upwardly, then horizontally outwardly and then downwardly and is received within the flange 12^a 25 of the bottom plate, the reflector being spaced from the bottom plate 12 and forming therewith a chamber C within which the fumes evolved from the arc are primarily received. The reflector is provided on either 30 side with tubular extensions 27^a and 27^b which pass upwardly and communicate with the tubes carrying the descending gases, which in the embodiment of my invention here shown are the tubes 10, 11^a. These extensions 35 communicate with the inner globe around the lower edge of the reflector and adjacent to the inner wall of the inclosing globe.

The lower electrode 32 is carried by the 40 electrode supporting arm 33 in the usual manner, which arm passes through a sleeve 34 secured to and suitably insulated from the bottom plate 12 of the lamp. An arm 35 may be secured to the lower end of the sleeve 45 34 and electrically connected to the electrode 32, if desired, in order to avoid the resistance of the lower electrode.

It will be understood that the electrodes 50 may be fed and regulated in any desired manner, and I have not deemed it necessary, therefore, to show such mechanism. Usually, however, I prefer a focusing mechanism, that it to say, a mechanism which feeds the electrodes in such a way as to maintain 55 the arc substantially stationary with reference to the lamp itself.

In operation, the fumes evolved from the 60 arc ascend through the opening 30 formed in the reflector about the economizer 27 and are received within the chamber C. The gases ascend into the recesses formed by the

hollow bosses 13, 13^a and through the two tubes 11 and 10^a, which communicate with these two recesses, to the respective depositing chambers A and B in the shell 1, through 65 which the gases must pass before they descend through the tubes 10, 11^a and the extensions 27^a and 27^b and thus pass downwardly around the reflector adjacent the inclosing globe to which they are returned. 70 During this circulation, the solidifiable products of combustion are largely deposited in the condensing chambers A and B so that when they are returned to the inclosing globe they are sufficiently purified to prevent an 75 appreciable deposit on said globe.

With my novel form of arc inclosure, it will be seen that the gases in their circulation are compelled to pass throughout the depositing chambers A and B, and such forced 80 passage promotes the deposit of the solidifiable matter within these chambers.

While I have illustrated and described the preferred form of my invention, it will be understood that numerous modifications 85 could be made without departing from the spirit thereof. For example, while I have shown four tubes, two tubes for the ascending and two for the descending gases, this number may be varied, though I prefer to have 90 at least two tubes for the descending gases, as such an arrangement subjects the arc to the same influences and conditions on either side so far as the draft is concerned and thus tends to keep the same steady. It will be 95 understood, therefore, that I do not desire to limit my invention to the details shown, except in so far as it is limited by the scope of the claim.

What I claim as new and desire to secure 100 by Letters Patent of the United States, is:—

In an arc lamp, an arc inclosure comprising an inclosing globe, a bottom plate for the lamp provided with bosses on its upper side forming recesses, a shell located above and remote from the globe forming a depositing chamber for the fumes evolved from the arc, tubes communicating with said chamber and with the recesses formed by said bosses, and a reflector loosely surrounding the upper 110 electrode and forming with said bottom plate a chamber in which the gases evolved from the arc are received, said reflector being provided with hollow extensions projecting upwardly to and communicating with a portion 115 of said tubes.

In witness whereof, I have hereunto set my hand this sixth day of March, 1914.

ANDRÉ BLONDEL.
